PRESSURE MEANS FOR WRINGER ROLLS

Julian L. Perkins, West Springfield, Mass., assignor to Perkins Machine and Gear Company

Application January 14, 1938, Serial No. 185,022

7 Claims. (CL. 68—263)

This invention relates to improvements in wringers and is directed more particularly to tension or pressure mechanism for the rolls of wringers.

5 The principal objects of the invention are directed to the provision of novel means for tensioning the rolls of a wringer or putting the wringer rolls under tension so that they apply pressure to material passing through the said rolls.

Various novel features and advantages of the invention will be hereinafter more fully referred to in connection with the accompanying description of the preferred form of the invention, reference being had to the drawings wherein:

Fig. 1 is a partial side and longitudinal sectional elevational view of a wringer embodying the novel features of the invention;

Fig. 2 is a transverse sectional elevational view 20 on the line 2—2 of Fig. 1; and

Fig. 3 is a perspective view of a part of the tension mechanism of the invention.

Referring now to the drawings more in detail the invention will be fully described.

25 A wringer head is represented at 2 and an end frame member is represented by 4 which may be connected together in any suitable manner as by a longitudinal member 6 to form a wringer frame structure. A lower roll 8 has one end portion 30 of its shaft 10 journaled in a bearing 14 and its other end 12 is operatively connected to a roll drive shaft 16.

The head 2 may contain reversing gearing of any well known form for driving the shaft 16. 35 A bearing 18 of the head is shown in which there are bushings for supporting the shaft 16. The reversing gearing forms no part of the present invention and therefore need not be described it being understood that shaft 16 is driven for 40 driving shaft 12.

An upper frame 22 commonly called an operating member carries an upper roll 24 for co-acting with the lower roll 8. This roll 24 has the ends of its shaft journaled in hubs 26 at 45 opposite ends of the operating member 22. Rolls 28 are journaled in the ends of the operating member 22 which with the hubs 26 releasably lock the operating member to receivers 30. The receivers 30 one in the head 2 and one in the end frame 4 are similar so that the one associated with the head only need be described.

As shown in Fig. 2 receiver 30 at its upper end is provided with a vertically disposed slot 32 leading into recesses 35 having cam surfaces 50 34.

A lower vertically disposed slot 36 is provided in the receiver which is of a width substantially equal to the diameter of the bearing 18 so that the receiver may move up and down. As stated there is a receiver associated with frame end 5 4 and formed similarly to that associated with the head so as to be movable up and down.

A pair of spring members 40 and 42 extend longitudinally of the wringer the ends of which diverge more or less as shown in Fig. 1. Opposite ends of the upper spring are seated in seats 44 and 46 of the head 2 and end frame 4 respectively. The lower spring member has its ends seated in seats 48 of the receiver 30 as shown clearly in Fig. 2.

15 A device 50 which may be called an expander is provided. This has an upper plate 52 against which the upper spring 40 abuts and a lower plate 54. Transverse spring separating parts 56 between the springs 40 and 42 are connected by 20 side plates 58 to the members 52 and 54. An adjusting screw 60 carrying a manually engageable part 62 is in threaded engagement with the part 54 so that its end may abut the lower spring 42.

25 By moving the screw 60 in and out the central portions of the springs are moved towards one another or are allowed to separate. For instance as the screw 60 is screwed inwardly the central part of the lower spring 42 is brought 30 towards the central part of the upper spring 40 so that separators 56 tend to separate the ends of the springs. The closer the central parts of the springs the more pressure is exerted on the receivers or the more spring resistance is 35 offered to upward movement of the receivers.

In the drawings the receivers are shown in their lowermost position the upper sides of openings 36 of the receivers resting on hubs 18 and 14 of the head and frame end. The springs may 40 be tensioned so that the receivers are yieldingly held in this lower position and this may be called initial tension. The roll 28 and hub 26 of the operating member 22 are shown in Fig. 2 as they are positioned when the operating member is in 45 its neutral inoperative position with the upper roll 24 resting on the lower roll 8.

In such a position the rolls are not under tension and the upper roll may be moved upwardly by lifting the operating member. The operating 50 member with its roll resting on the lower roll 8 is swingable in opposite directions from a central inoperative position to an operative position at either side thereof.

When the operating member is moved from its 55

- central inoperative position to an operative position at either side of the inoperative position the rolls 28 are caused to roll onto the cam surfaces 34 of the receivers and the said rolls come to rest in 5 the recesses 35, elevating the receivers slightly against the action of the springs. The springs, rolls and cam surfaces act to releasably lock the operating member in an operative position with the upper roll on the lower roll.
- 10 In this position the receivers may move upwardly against the action of the spring when material, such as clothes, is passed between the rolls so that the springs apply pressure to the rolls and material passed therebetween.
- 15 From the foregoing it will be observed that the pressure applied to the rolls may be varied by moving the central part of the springs towards and away from one another. The mechanism is simple in form and adapted to facilitate small 20 variations in pressure within a wide range of pressures.

What it is desired to claim and secure by Letters Patent of the United States is:

- 25 1. The combination in a wringer of, a frame, a roll journalled in the frame on a fixed axis, a second removable roll, members slidale relative to the frame at opposite ends of said rolls, means for releasably locking said second roll to said members, abutments at the lower side of the 30 frame at opposite ends thereof, and upper and lower springs connected together intermediate their ends extending longitudinally of the frame with the opposite ends of said springs engaging said abutments and said slidale members.
- 35 2. The combination in a wringer of, a frame, a roll journalled in the frame on a fixed axis, a second removable roll, members slidale relative to the frame at opposite ends of said rolls, means for releasably locking said second roll to said 40 members, abutments at the lower side of the frame at opposite ends thereof, upper and lower springs extending longitudinally of the frame having their opposite ends engaging the abutments and slidale members, and adjustable expanding means intermediate the ends of said 45 springs acting thereon to separate said springs.
3. The combination in a wringer of, a frame, a roll journalled in the frame on a fixed axis, a removable second roll, members slidale relative 50 to the frame at opposite ends of said rolls, means to releasably lock the second roll to said members, abutments at the lower side of the frame at opposite ends thereof, upper and lower springs extending longitudinally of the frame having their opposite ends engaging the abutments and slidale members, expanding means intermediate the ends of said 55 springs acting thereon to separate said springs including spaced parts between and intermediate the ends of said springs, and parts above

and below said springs acting to press said springs together.

4. The combination in a wringer of, a frame, a roll journalled in the frame on a fixed axis, a second roll journalled in the frame about an axis 5 movable with respect to said frame, members slidale relative to the frame at opposite ends of said rolls, abutments at the lower side of the frame at opposite ends thereof, upper and lower springs extending longitudinally of the frame 10 having their opposite ends engaging the abutments and slidale members, expanding means intermediate the ends of said springs acting thereon to separate said springs including members at the outer sides of said springs intermediate 15 the ends thereof relatively movable towards and away from one another, and other members at the sides thereof extending between said springs.

5. The combination in a wringer of, a frame, a roll journalled in the frame on a fixed axis, a second roll journalled in the frame about an axis 20 movable with respect to said frame, members slidale relative to the frame at opposite ends of said rolls, abutments at the lower side of the frame at opposite ends thereof, separate upper 25 and lower springs extending longitudinally of said frame, the ends of the upper spring engaging said abutments and the ends of the lower spring engaging said slidale members, a member intermediate the ends of said springs having a part 30 extending across the outer side of the upper spring and parts at the sides thereof extending between said springs, and means abutting the outer side of the lower spring and exerting pressure thereon. 35

6. Tension mechanism for the rolls of a wringer comprising, upper and lower relatively flat springs having ends adapted to engage the relatively movable frame and roll carrying parts of a wringer, members extending transversely at the 40 outer sides of and intermediate the ends of said springs holding the intermediate portions of said springs in fixed spaced relation, and transverse members extending between said springs at opposite sides of said intermediate portions of the 45 springs tending to wedge them apart so that the ends of said springs diverge.

7. Tension mechanism for the rolls of a wringer comprising, upper and lower relatively flat springs having end portions adapted to engage the relatively movable frame and roll parts of a wringer, and means for urging adjacent ends of the said 50 springs apart including, a member having a part extending across the outer side of one spring intermediate its ends, a part adjustable in said member 55 abutting the outer side of the other spring, and portions associated with said member extending between said springs at the sides of said parts.

JULIAN L. PERKINS.
